FRANK A. MEYER, OF NORWOOD, PENNSYLVANIA, ASSIGNOR TO WESTINGHOUSE ELECTRIC & MANUFACTURING COMPANY, A CORPORATION OF PENNSYLVANIA

AUTOMATIC STOP GOVERNOR

Application filed August 1, 1928. Serial No. 296,832.

My invention relates to an automatic stop governor for a prime mover, and it has for its object to provide apparatus of the character designated which shall be simple, and also reliable in operation.

Another object is to provide an automatic overspeed stop governor which may be set without stopping the prime mover, and a further object is to provide means for testing such a governor at a speed less than the overspeed for which it is set, without first shutting down the prime mover.

Another object of the invention is to provide an automatic overspeed stop governor of the hydraulic or fluid pressure type.

A further object is to provide an automatic stop governor which shuts off the supply of motive fluid upon failure or predetermined diminution of the fluid pressure at the inlet of an impeller for a fluid pressure governor.

In accordance with my invention, I provide an element subjected to fluid pressure varying as a function of the speed of the prime mover and bias said element in opposition to the fluid pressure by a constant force, such as the force of gravity of a number of weights. The amount of said force is such as to exceed or equal the force of said fluid pressure until a predetermined overspeed is exceeded, when said element is effective to shut off the supply of motive fluid to the prime mover.

The above and other objects are effected by my invention, as will be apparent from the following description and claims taken in connection with the accompanying drawing, forming a part of this application, in which:

The single figure is a diagrammatic view of my automatic stop governor controlling the throttle valve of a prime mover parts thereof being shown in section.

Referring now to the drawing in detail, I show my novel governor applied to a prime mover, of which is shown only a fragment of the horizontal rotor shaft 10, and a fragment of the casing 11, supporting a bearing 12 for the shaft. The shaft 10 has an impeller 14 mounted directly thereon and disposed within an impeller housing 15. The impeller provides a fluid pressure which varies as the square of the speed of the prime mover. The

fluid which is used to provide this pressure is preferably lubricating oil which is also used for lubricating the bearing 12.

Motive fluid for the prime mover, hereinafter referred to as steam, is supplied thereto through a throttle valve 16 and a governor valve 17. The governor valve 17 is controlled and operated by a fluid pressure governor 18, having a piston 19 disposed in a cylinder 20. The piston is operatively connected to the valve 17, and is biased to open the valve by a spring 20'. The piston 19 is also subjected to the pressure developed by the impeller 14, which is transmitted thereto through a conduit 21, and which acts on the piston in opposition to the spring 20' and to close the valve 17.

Upon increase in speed, the increased oil pressure moves the piston 19 to decrease the valve opening 17, and upon a decrease in speed, the decreased pressure permits the spring 20 to move the piston 19 for increased valve opening.

It will be apparent that this form of governor for the valve 17 is shown merely for example, and that any type of speed governor may be used, or that a governor may be omitted.

At 23 I show a reservoir for supplying oil to the impeller 14. Oil from the reservoir 23 flows by gravity to an ejector 24, which is motivated by oil pressure transmitted through a conduit 25 from the impeller 14, and which supplies the oil at a lower pressure to the inlet of the impeller through a conduit 26. The conduit also supplies oil to the bearing 12.

The throttle valve 16 is operated by a throttle valve operating mechanism 28 consisting of a piston 29 connected to the throttle valve, a cylinder 30, a spring 31, and a screw-threaded stem 32. A passage 33 is provided in the piston 29 for providing communication between the upper and lower ends of the cylinder 30. The upper end of the passage is adapted to be covered by the lower end of the stem 32. Fluid pressure is supplied through a conduit 34 to the lower end of the cylinder 30 to actuate the piston 29 in valve opening direction, and a drain conduit 35

communicates with the cylinder 30 above the piston 29 and conveys the oil drained therefrom to the reservoir 23. A restricted orifice 27 is interposed in the conduit 34 to limit the flow of fluid therethrough.

The valve operating mechanism 28 is controlled by my novel automatic stop governor 36, which will now be described. This governor includes a casing 37 having a cylindrical bore 38, a second cylindrical bore 39 and a third cylindrical bore 40. Disposed within the housing 37 is an element 41, which has a piston 42 in the cylindrical bore 39, a sleeve portion 46 extending therefrom, the end of which fits in the cylindrical bore 40, and piston portions 43, 44 and 45 carried by the sleeve 46 and fitting in the bore 38. The sleeve portion 46 is provided with an annular row of ports 47 above the piston portion 43, a second row of ports 48 between the piston portions 43 and 44, and a third row of ports 49 between the piston portions 44 and 45. The casing 37 has a port 50 communicating with the impeller 14 through a conduit 51, and a port 52 communicating with the conduit 34. The casing 37 is also provided with ports 54 and 55 communicating with the drain conduit 35.

Extending through the upper end of the casing 37 is a stem 56, on the upper end of which is formed a disc 57 adapted to carry a plurality of weights 58.

Disposed within the sleeve portion 46 is a valve member 59, having piston portions 60, 61 and 62. The lower end of the valve member 59 is secured to a piston 63 which is biased downwardly by a compression spring 64. The piston 63 is biased upwardly, however, by the pressure of the fluid supplied to the impeller 14 through the conduit 26, which pressure is conveyed to the lower end of the casing 37 through a conduit 64'.

A chamber 65 is formed between the piston portion 45 and a shoulder 66 which connects the cylindrical bores 40 and 38. A conduit 67 communicates with the chamber 65 and also with the conduit 51, and interposed in the conduit 67 is a hand valve 68, by means of which the supply of fluid under pressure to the chamber 65 may be controlled. A small orifice 65' is formed in the sleeve 46 to permit a restricted escape of fluid from the chamber 65. A pressure gauge 69 communicates with the conduit 67 and indicates the pressure in the chamber 65.

55 A conduit 70, communicating with the conduit 51, is provided for supplying fluid pressure from an auxiliary source in starting the prime mover.

The operation of the above described apparatus is as follows:

The parts are shown in the position of normal operation, in which the pressure of the oil supplied to the impeller is sufficient to raise the piston 63 against the spring 64, and in which the pressure developed by the im-

peller is not sufficient to raise the piston 42. In this position the piston portion 60 is disposed immediately above the port 47 and the piston portion 44 is disposed below the port 52. Fluid pressure from the conduit 51 is therefore transmitted through the port 47, the ports 48, the port 52, the conduit 34 and the orifice 27 to the throttle valve operating mechanism 28 to retain the same in open position.

Assume now that the prime mover exceeds a predetermined over-speed. The weights 58 are so adjusted that at such times the impeller pressure on the piston 42 overcomes the force of gravity of the weights and the element 41, and raises the piston 42. The piston portion 60 thereupon covers the ports 47 and cuts off further supply of fluid pressure to the throttle valve operating mechanism. The piston portion 44 also moves upwardly above the port 52, placing the latter in communication with the drain port 54.

The oil in the throttle valve operating mechanism is free, therefore, to flow through the conduit 34 and the ports 52 and 54, to the drain conduit 35, which it does under force of the spring 31. This flow is restricted by the orifice 27. However, only a slight flow is required, since the passage 33 opens as soon as the piston 29 begins to move and permits the rapid escape of fluid from beneath the piston. The spring 31 thus moves the piston to effect a rapid closing of the throttle valve.

When the prime mover speed is restored to normal, the element 41 falls by force of gravity to its normal position, in which position fluid under pressure is conveyed to the throttle valve operating mechanism but escapes through the passage 33 without having any effect on the piston 29 until the hand wheel 32 is operated to lower the stem 32. The orifice 27 restricts the flow of fluid at this time to prevent a loss of pressure in the conduit 51.

When it is desired to test the automatic stop governor and the throttle valve operating mechanism, at normal speed or any speed below the predetermined overspeed, the hand valve 68 is slowly opened to admit fluid under pressure from the conduit 51 to the chamber 65. The pressure in said chamber builds up and acts on the piston portion 45 until the element 41 moves upwardly to trip the valve operating mechanism. The pressure at which the element 41 moves may be determined from the gauge 69, from which may be calculated the overspeed at which the governor is set. After the governor is tested, the valve 68 is closed and the fluid in the chamber 65 slowly escapes through the orifice 65', releasing the pressure therein.

The low pressure trip operates as follows:

In case of failure of oil pressure in the conduit 26, which supplies oil to the impeller 14, the spring 64 forces the piston 63 and the valve member 59 downwardly. The piston

60, as before, covers the ports 47 and cuts off the supply of fluid pressure, and the piston portion 61 moves below the ports 49, thereby placing the ports 52 in communication with the drain conduit 35 through the ports 48, 49 and 54. The pressure in the cylinder 30 is released, as in the case of overspeed, and the throttle valve operating mechanism is tripped to close the throttle valve.

10 Upon restoration of the minimum oil pressure in the conduit 26, the piston 63 and the valve member 59 are moved upwardly to normal position and a restricted flow of oil is again supplied to the throttle valve operating mechanism. The stem 32 may then be lowered and raised to again open the throttle valve.

15 From the above description, it will be apparent that I have provided an automatic stop overspeed governor, which may be set without stopping the prime mover, by adding to or removing from the weights 58 on the disc 57. It will also be noted that the governor automatically resets itself, except that 20 when testing it is necessary to close the valve 68.

25 An advantage of my novel governor is that it may be placed at any desired location, since it is hydraulically connected to the apparatus with which it cooperates.

30 A further advantage is that the force opposing the governing force remains constant, and does not increase as in the case of spring force. Hence, when the predetermined overspeed is exceeded and the element 41 begins 35 to move, it continues to do so without further increase in speed.

The low pressure trip of my automatic stop 40 governor provides a special protection for the fluid pressure governor, which increases the fluid admission with decrease in fluid pressure. In case of failure or abnormal drop in pressure of fluid supplied to the impeller, the pressure supplied to the governor would 45 be correspondingly decreased and admit an excessive amount of motive fluid. The low pressure trip guards against such a possibility by closing the throttle valve.

50 While I have shown my invention in but one form, it will be obvious to those skilled in the art that it is not so limited, but is susceptible of various changes and modifications without departing from the spirit thereof, and I desire, therefore, that only such limitations shall be placed thereupon as are imposed by the prior art or as are specifically set forth in the appended claims.

What I claim is:

1. The combination with a prime mover 55 and a throttle valve therefor, of mechanism for operating said throttle valve, means providing a fluid pressure varying as a function of the speed of the prime mover, an automatic stop governor including an element having 60 an area of surface subjected to said fluid

pressure and adapted to control said valve operating mechanism to close the throttle valve upon a predetermined pressure, means for applying fluid pressure to an additional area of surface of said element to effect movement thereof at a pressure on the first-mentioned area of less than the predetermined pressure, and means for indicating the pressure on said additional area. 70

2. The combination with a prime mover 75 and a throttle valve therefor, of means for operating the throttle valve, means providing a fluid pressure varying with the speed of the prime mover, an automatic stop governor responsive to said fluid pressure and adapted 80 to control the throttle valve operating means to effect complete closing thereof, means for adjusting said governor to operate at a predetermined pressure, and means independent of said adjusting means for effecting operation of said governor at a pressure less than the predetermined pressure when testing the governor. 85

3. The combination with a prime mover 90 having a throttle valve and a governor valve controlling the admission of fluid thereto, of means providing a fluid pressure varying as a function of the speed of the prime mover, means providing a supply of fluid to said means, a governor responsive to said pressure 95 for regulating the governor valve, and means responsive to said supply for effecting complete closing of said throttle valve.

4. The combination with a prime mover 100 having a throttle valve and a governor valve controlling the admission of fluid thereto, of means providing a fluid pressure varying as a function of the speed of the prime mover, means providing a supply of fluid to said 105 means, a governor responsive to said pressure for regulating the governor valve, and means responsive to the pressure of the fluid supplied and for effecting complete closing of the throttle valve.

5. The combination with a prime mover 110 having a throttle valve and a governor valve controlling the admission of fluid thereto, of means providing a fluid pressure varying as a function of the speed of the prime mover, means providing a supply of fluid to said 115 means, a governor responsive to said pressure for regulating the governor valve, and means for effecting complete closing of the throttle valve upon failure of said supply.

In testimony whereof, I have hereunto subscribed my name this 27th day of July, 1928.

FRANK A. MEYER.

CERTIFICATE OF CORRECTION.

Patent No. 1,816,020.

Granted July 28, 1931, to

FRANK A. MEYER.

It is hereby certified that error appears in the printed specification of the above numbered patent requiring correction as follows: Page 3, line 119, insert the following as claim 6 :

6. The combination with a prime mover and a throttle valve therefor, of mechanism for operating said throttle valve, means providing a fluid pressure varying as a function of the speed of the prime mover, an automatic stop governor including an element having an area of surface subjected to said fluid pressure and adapted to control said valve operating mechanism to close the throttle valve upon a predetermined pressure, and means for applying fluid pressure to an additional area of surface of said element to effect movement thereof at a pressure on the first-mentioned area of less than the predetermined pressure.
and that the said Letters Patent should be read with this correction therein that the same may conform to the record of the case in the Patent Office.

Signed and sealed this 6th day of October, A. D. 1931.

**M. J. Moore,
Acting Commissioner of Patents.**
